Des. 215,020

Patented Aug. 19, 1969

215,020

COIN CHUTE OR THE LIKE

Robert K. Unter, Rockford, Ill., assignor to Keystone Consolidated Industries, Inc., a corporation of Delaware

Filed July 19, 1968, Ser. No. 12,829

Term of patent 14 years

Int. Cl. D20—01

U.S. Cl. D52—3

FIG. 1.

FIG. 2.

FIG. 3.

FIG. 4.

FIG. 5.

FIGURE 1 is a perspective view of a coin chute or the like, embodying my new design;

FIG. 2 is a top plan view thereof;

FIG. 3 is a front elevational view thereof;

FIG. 4 is a bottom plan view thereof; and

FIG. 5 is a side elevational view thereof.

I claim:

The ornamental design for a coin chute or the like, substantially as shown.
